HOWARD WATERS DOUGHTY, OF AMHERST, MASSACHUSETTS

SPRINKLER HEAD

Application filed June 26, 1928. Serial No. 288,466.

This invention relates to fire-extinguishing apparatus and particularly to sprinkler heads adapted to deliver extinguishing liquid automatically when a fire occurs in the vicinity of one or more of the heads which are distributed about the premises to be protected.

10 Sprinkler heads as used heretofore comprise a body adapted to be connected to a pipe line or liquid receptacle and having an outlet opening through which the liquid is discharged. The outlet is sealed normally by a closure which is held in engagement therewith by a fusible link. When the temperature in the vicinity of a head rises to a predetermined point the link fuses and the pressure of the liquid lifts the closure so that the liquid is permitted to escape in the form of spray, and is distributed over the surrounding surface.

20 It sometimes happens that the closure does not tightly seal the outlet and leakage may occur with resulting damage to material in the vicinity of the head. Moreover, in certain types of extinguishers the pressure required to eject the liquid is developed by the heat resulting from the fire. In such extinguishers it is desirable that the closure should not be released prematurely.

25 It is the object of the present invention to provide an improved sprinkler head which affords a tight seal for the liquid which, however, is released under appropriate conditions to permit the head to function.

30 A further object of the invention is the provision of a sprinkler head the operation of which is subject to the dual control of temperature and the pressure of the liquid, so that the conditions under which the liquid is permitted to escape can be more accurately determined.

35 In carrying out the invention, I provide a sprinkler head of the ordinary type including, for example, a base and a support threadedly connected thereto for the fusible link.

40 An opening is provided in the base which is adapted to be connected to a pipe line or to a receptacle for liquid. A similar opening is provided in the support for the link and the two openings register when the parts are assembled.

The base is formed with a shoulder surrounding the opening therein and a corresponding shoulder is provided at the bottom of the link support. Between these shoulders I insert a diaphragm of frangible material, preferably of metal foil such as aluminum foil, tin foil or the like. The thickness of the foil may be determined with reference to the pressure at which it is intended to rupture and the area which is exposed to the pressure. Preferably the foil is mounted 55 between two metal washers having openings therein registering with the openings in the base and the link support. The washers may be coated before assembling with a suitable 60 luting material such as nitro-cellulose paste or a mixture of glycerine and litharge to ensure a tight joint.

65 I provide a closure which is adapted to rest on the upper washer above the opening therein. A thin metal cup-shaped disk is suitable. One end of the fusible link engages this closure while the other is held by a screw in the link support which permits suitable adjustment of the parts.

70 When the sprinkler head is assembled, the washers enclosing the foil diaphragm are firmly held between the shoulders on the base and link support, thus sealing the outlet. The disk is likewise held firmly above the 75 foil diaphragm by the fusible link. Leakage cannot occur, therefore, even if the link is loosened slightly unless the pressure is sufficient to rupture the diaphragm. Normally the pressure in an ordinary system 80 will be sufficient to rupture the diaphragm only when the pressure exerted by the disk is removed as when the link is fused. In systems in which the pressure is developed by 85 the heat of the fire liquid cannot escape until the temperature rises to a predetermined point.

90 In the operation of the device as described, upon the occurrence of a fire the fusible link 95 is melted when a certain temperature is attained. The pressure on the disk is thus released and the pressure of the liquid in the system is permitted to rupture the diaphragm, thus releasing the liquid which is 100

sprayed over the surrounding surface. In systems in which pressure is developed by heat the liquid will not be released immediately when the link is fused unless the temperature is high enough to develop the required pressure. As soon as that temperature is attained the pressure will rupture the diaphragm and the liquid will be sprayed over the surrounding surface. The dual control of temperature and fluid pressure is particularly desirable where the expansive agent is a substance such as ammonia water. Ammonia water is very sensitive to changes of temperature, and it frequently happens that the temperature during the summer is high enough to cause sufficient expansion to distort the diaphragm although not high enough to rupture the same and cause discharge. Such distortion weakens the diaphragm and may even develop pine holes. Repeated strains of that sort may weaken the diaphragm to such an extent as to permit discharge at less than the predetermined temperature. By having the diaphragm subject to temperature control as well as fluid pressure control such strains on the diaphragm can be avoided and the diaphragm maintained at all times in first class condition.

The invention will be better understood by reference to the following specification and accompanying drawing in which

Fig. 1 is a sectional view of the sprinkler head and

Fig. 2 is a view in perspective of the diaphragm and washers.

Referring to the drawing, 5 indicates the base having a threaded opening 6 therethrough whereby the head is assembled with a pipe or receptacle for liquid. The base is provided with a threaded flange 7 to receive the link support having an opening 8 registering with the opening 6 and a loop 9. A screw 10 supported in the loop is slotted at 11 to engage one end of a link comprising, for example, members 12 which are secured together with a metal which is fusible at relatively low temperatures. A locking clamp 13 secures the screw when it has been adjusted.

Two washers 14 and 15 are disposed between the shoulders 16 and 17 on the base and link support respectively and a diaphragm 18 of frangible material such as metal foil is disposed between the washers, each of which has a central opening 19. The foil and washers may be cemented together as hereinbefore indicated.

A disk 20 rests on the opening in the washer 15 and is engaged by the end of the fusible link. The disk forms a closure which is released when the link is fused. The diaphragm is then subjected to the pressure of the liquid in the pipe or receptacle to which the sprinkler head is connected and is ruptured when a sufficient pressure is applied thereto.

The device as described affords a simple and satisfactory sprinkler head which avoids the difficulties met heretofore. The dual control of the release is particularly effective in preventing premature release of the liquid in the system.

Various changes may be made in the details of construction and arrangement of the parts without departing from the invention or sacrificing any of the advantages thereof.

I claim:

1. In a sprinkler head for use in fire extinguishers in which the pressure normally maintained is below the operating pressure, the combination of a base having an opening affording a passage for fluid from the extinguisher, and means subject to dual control of temperature and fluid pressure, said means preventing the escape of fluid through said opening until the pressure in the extinguisher reaches a predetermined amount above that normally maintained.

2. In a sprinkler head for use in fire extinguishers in which the pressure normally maintained is below the operating pressure, the combination of a base having an opening affording a passage for fluid from the extinguisher, and means subject to dual control of temperature and fluid pressure including a frangible diaphragm, said means preventing the escape of fluid through said opening until the pressure in the extinguisher reaches a predetermined amount above that normally maintained.

3. In a sprinkler head for use in fire extinguishers in which the pressure normally maintained is below the operating pressure, the combination of a base having an opening affording a passage for fluid from the extinguisher, and means subject to dual control of temperature and fluid pressure including a frangible diaphragm and a fusible link associated therewith, said means preventing the escape of fluid through said opening until the pressure in the extinguisher reaches a predetermined amount above that normally maintained.

4. In a sprinkler head the combination of a base having an opening affording a passage for liquid, a fusible link support connected to the base and having an opening registering with the opening in the base, a frangible diaphragm between the base and support, a disk engaging the diaphragm and a fusible link between the disk and the support whereby rupture of the diaphragm is prevented until the fusible link is released.

5. In a sprinkler head the combination of a base having an opening affording a passage for liquid, a fusible link support connected to the base and having an opening registering with the opening in the base, washers between the base and support, a

frangible diaphragm between the washers, a disk engaging the diaphragm and a fusible link between the disk and the support whereby rupture of the diaphragm is prevented until the fusible link is released.

5 In testimony whereof I affix my signature.
HOWARD WATERS DOUGHTY.
